UNITED STATES PATENT OFFICE.

JOHN S. TILLEY, OF WEST TROY, NEW YORK.

IMPROVEMENT IN ADJUSTABLE SCAFFOLDS.

Specification forming part of Letters Patent No. 140,858, dated July 15, 1873; application filed June 7, 1873.

To all whom it may concern:

Be it known that I, JOHN S. TILLEY, of West Troy, in the county of Albany and State of New York, have invented a new and Improved Adjustable Scaffold, of which the following is a specification:

For adjusting the scaffolds of wall-plasterers and ceiling-decorators, high or low, according to the height of the room, I propose to have short trestle-heads mounted on, say, three legs, with a vertically-adjusting standard in each head having a fastening to hold it at any height, and having a couple of plates clamped to it at each side near the top, so that they can be readily adjusted to form, with the standard, a T-head whereon the scaffold-boards may rest flatwise, or they may be turned up endwise and project above the end of the standard so as to retain a plank placed edgewise on the top of the standard. When, as in the case of decorating ceilings, it is desirable to build broad scaffolds by laying the scaffold boards or planks, extending from one trestle-head to another, and arranged edgewise to support the scaffold-boards.

In order to pack the benches compactly and economically, in regard to space for shipping or storing them, I propose to have the legs jointed to them so as to fold over on the sides in a compact form when not in use, and I arrange them, in connection with notches or shoulders on the heads, so that when in use the ends of the legs bear against the walls or shoulders of the notches, and so transmit the force directly from one to the other without injury to the joints.

Figure 1 is a side elevation of one of my improved adjustable scaffold-trestles; Fig. 2 is a sectional elevation; and Fig. 3 is a plan view of a couple of the trestles with the legs folded together and packed for shipping.

A is the head of the trestles. B are the legs, which are hinged to it at C, and seated at the upper ends in notches in the sides of the body

against shoulders D, as aforesaid, and they are connected below the front by a hook, E, and staples to prevent them from slipping and spreading apart at the lower end on the floor.

Any other fastening may be used for this purpose that will answer.

F is the vertically-adjustable standard, arranged in the head A, and having pin-holes G to hold it at any height by a pin, or notches H to be held by a projection, I, on one of the legs. J represents the plates clamped to the sides near the head by a bolt, K, and thumb-nut L. These plates are to be adjusted horizontally, as shown in Fig. 1, to receive the scaffold-planks M on them flatwise when only a narrow scaffold is wanted, as when decorating walls. They are to be adjusted vertically, as in Fig. 2, when a wide scaffold is wanted, as when decorating a ceiling, to receive a plank, N, edgewise between them, the plank being thus supported at each end and supporting the scaffold-planks O on its upper edges.

The trestles are arranged in pairs, as in Fig. 3, the side legs folded side by side, as seen at the top of the figure, and the end legs folded against the ends, as seen thereat, in a compact way, so as to be economically packed in a case wherein the standards F and plates J, being removed from the bench-tops, can be placed alongside of the benches.

Having thus described my invention, I claim as new and desire to secure by Letters Patent—

1. The combination of the vertically-adjustable standards having the adjustable plates J with the trestles A B, substantially as specified.
2. The heads A and legs B jointed together and arranged in relation to the shoulders D and the ends of the legs, as described.

JNO. S. TILLEY.
